Primary Examiner — Patricia A Palasik(74) *Attorney, Agent, or Firm* — Muncy, Geissler, Olds & Lowe, P.C.(57) **CLAIM**

The ornamental design for a retainer for rolling bearing, as shown and described.

DESCRIPTION

FIG. 1 is a front view of the retainer for rolling bearing; FIG. 2 is a back view thereof;

FIG. 3 is a right side view thereof;

FIG. 4 is a left side thereof;

FIG. 5 is a top view thereof;

FIG. 6 is a bottom view thereof;

FIG. 7 is a respective view thereof;

FIG. 8 is a sectional view taken along line 8-8 in FIG. 1;

FIG. 9 is an enlarged partial view along line 9-9 in FIG. 1;

FIG. 10 is an enlarge partial view along line 10-10 in FIG. 7; and,

FIG. 11 is an enlarge partial view along line 11-11 in FIG. 7.

The broken line showing is for the purpose of illustrating environmental structure and forms no part of the claimed the design.

1 Claim, 6 Drawing Sheets(56)
